REGENERATOR OF A COKE OVEN BATTERY

Charles V. McIntire, Short Hills, N. J., assignor
to Semet-Solvay Engineering Corporation, New
York, N. Y., a corporation of New York

Application August 4, 1936, Serial No. 94,146

4 Claims. (Cl. 202—268)

This invention relates to coke ovens of the kind in which regenerators are provided for the alternate heating of gas and air or air alone and which regenerators are arranged below the coking chambers, extend longitudinally of these chambers, and as shown, for example, in United States Patent 1,947,500 of February 20, 1934, are divided by partition walls extending longitudinally of the battery into regenerator compartments.

In designing such partition walls, it is necessary to provide for expansion joints therein which permit longitudinal expansion of the coke oven battery and at the same time have the partition walls of gas tight construction, so that leakage of gas from one regenerator compartment into the next compartment will not take place.

This invention relates to the construction and design of these partition walls to provide effective expansion joints therein, permitting longitudinal expansion of the battery while also providing partition wall structures which effectively prevent leakage of gas from one regenerator compartment to another, and moreover, serve to buttress or strengthen the cross-wise extending walls disposed beneath the coking chambers parallel thereto and defining the sides of the regenerators.

In the accompanying drawings forming a part of this specification and showing for purposes of exemplification a preferred form of this invention, without limiting the claimed invention to this illustrative instance:

Fig. 1 is a cross-wise vertical section of a coke oven battery taken longitudinally through a heating wall and the regenerator compartments therebeneath;

Fig. 2 is a fragmentary enlarged horizontal section through two contiguous partition walls embodying the improvement of the present invention, the section being taken on line 2—2 of Fig. 4 and extending through the even numbered courses of brick forming the partition walls;

Fig. 3 is a fragmentary enlarged horizontal section through two contiguous partition walls embodying the improvement of the present invention, the section being taken on line 3—3 of Fig. 4 and extending through the odd numbered courses of brick forming the partition walls;

Fig. 4 is a section taken in a vertical plane passing through the line 4—4 of Figs. 1, 2 and 3, showing the partition walls, viewed in the direction indicated by the arrows, in elevation and illustrating the staggered arrangement of joints in courses of brick forming the partition walls;

Fig. 5 is a fragmentary section through a par-

tition wall, taken in a vertical plane passing through the line 5—5 of Fig. 3, and shows the tongue and groove joints between the brick of contiguous courses constituting the partition wall;

Fig. 6 is a fragmentary sectional view somewhat diagrammatic in character and on a smaller scale than Fig. 3, the section being taken on line 3—3 of Fig. 4.

Referring to the drawing, there is shown in Figs. 1 and 2 a coke oven battery of the type more fully described in the aforementioned United States Letters Patent 1,947,500, involving a series of alternate horizontal coking chambers and heating walls 12 therefor, arranged side by side in a row. Regenerators situated below the coking chambers are defined by cross-wise extending walls 13 and longitudinally extending partition walls 14 hereinafter more fully described. As shown in Fig. 4, the partition walls 14 are constituted of courses of brick 10 referred to herein as even numbered courses and alternate courses of brick 11 referred to herein as odd numbered courses. In the embodiment of the invention shown on the drawings, three partition walls are provided, defining four regenerator compartments which are arranged so that cross-wise of the battery alternate regenerators feed air or gas to the heating flues while products of combustion are discharged through the remaining regenerators. As this invention is particularly concerned with the design and structure of the partition walls 14, and as the other features of the construction and operation of the battery disclosed in the accompanying drawings are fully described in the aforementioned patent, it is believed unnecessary to describe such other features in greater detail.

As shown in Figs. 2 to 5, each cross-wise extending wall is built up of silica brick 15. Each partition wall 14, in accordance with this invention, is constructed and designed to provide expansion joints permitting longitudinal expansion of the oven battery, while at the same time producing a gas tight barrier between the regenerator compartments at the opposite sides thereof, and reinforcing or buttressing the cross-wise extending walls 13. In the particular embodiment of the invention shown on the drawings each partition wall is built up of brick shapes disposed in courses; Fig. 2 representing a section through the bricks constituting the even numbered courses, while Fig. 3 shows the brick shapes in the odd numbered courses.

The even numbered courses of brick of each partition wall, as appears from Fig. 2, comprise

the brick 5 having a projecting portion 16 and a groove for receiving a tongue of brick 17. One end of brick 17 has a tongue for reception by a groove in one end of brick 18. The latter brick 5 is held in place by an angle brick 19 having a tongue which enters a groove in brick 20. One end of brick 18 is spaced from the end of brick 20 forming an expansion joint space 21. Brick 20, it will be noted, is of the same shape as brick 17, and like this brick, cooperates with a contiguous brick to define an expansion joint space. The projecting portion 22 of brick 19 extends over the face of brick 18 contiguous to the end thereof defining the expansion joint space 15 21, thus enclosing this space. The expansion joint spaces 21 and 21' (hereinafter referred to) are of sufficient size to permit the brickwork to reach its full expansion when heated without completely filling these spaces.

Bricks 5, 17, 18 and 19 define one side of the partition wall. The opposite side of this wall is defined by the bricks 23, 24 and 25 which may be of the shape shown in the drawings. Bricks 23 and 24 are joined by tongue and groove connections and end 26 of brick 24 is spaced from a filler brick 27 to form the expansion joint space 21'. Brick 27 has tongue and groove connections with bricks 17 and 26. Projecting portion of brick 25 extends over the end portion of brick 24 defining the expansion joint space 21', thus enclosing this space.

Referring to Fig. 3, the left side of each partition wall (viewing this figure) is constituted of bricks 31, 32 and 33 of the shape shown; brick 31 being bonded to brick 32 by a tongue and groove joint. Brick 33 has a projecting portion 34 which extends over the end portion of brick 32 and covers the expansion joint space 21 defined by the end of brick 32 and filler brick 35. The right side of the partition wall is constituted of bricks 36, 37, 38 and 39; brick 37 being bonded to brick 38 by a tongue and groove joint and brick 38 being bonded to brick 39 and filler brick 35 by tongue and groove joints as shown on the drawings. Brick 36 has a projection 40 which extends over the end portion of brick 37, which with filler brick 41, defines expansion joint space 21'. Brick 39 has a projection 42 which abuts the face of brick 38.

It will be noted from Fig. 4 that joints 43 between the bricks 23, 24 in the even numbered courses are staggered with respect to the joints 44 between the bricks 37, 38 of the odd numbered courses. A similar arrangement of staggered joints results between bricks 17, 18 of the even numbered courses on the one hand and those between bricks 31, 32 of the odd numbered courses on the other. It is noted the expansion joints 21, 21' formed in laying the several courses 60 of brick constituting the partition wall are aligned. As appears from Fig. 5, the brick of contiguous courses are bonded together by tongue and groove joints 50, i. e., bricks 18 and 24 have tongues on their bases which fit in grooves in the top surfaces of bricks 32 and 37 respectively, and the other bricks of each even numbered course are provided with tongues on their bases which fit in complementary grooves in the top surfaces of the bricks of the underlying odd numbered courses.

The bricks hereinabove referred to may be of silica or other high heat resisting refractory material suitable for the construction of the regenerating walls of a coke oven battery. All contacting brick surfaces shown on Figs. 2 and 3,

with the exception of the contacting surfaces between bricks 18 and 19; 18 and 23; 18 and 24; 17 and 24 and 24 and 25 (Fig. 2) and between bricks 32 and 33; 32 and 38; 32 and 37; 31 and 37 and 37 and 40 (Fig. 3) during the laying of the brick to form the walls, are bonded by a suitable fireclay mortar. The contacting surfaces between the brick enumerated in the preceding sentence are laid dry, i. e., no mortar is introduced therebetween. In effect this results in the production of partition walls each constituted of two substantially monolithic portions having surfaces thereof lying in a vertical plane extending the full height of the regenerator, one of which monolithic portions is made up of bricks 23, 24 (Fig. 2) and 37, 38, 39 (Fig. 3) having one end bonded with the wall shown at the top of Figs. 2 and 3, and the other end defining the expansion joint space 21'; and the other of which monolithic portions is constituted of bricks 5, 17, 18 (Fig. 2) and 31, 32 (Fig. 3) having one end bonded with the wall shown at the base of Figs. 2 and 3 and the other end defining the expansion joint space 21.

With reference to each cross-wise extending wall 13, it will be noted that at a plurality of spaced points at opposite sides thereof there are disposed the monolithic portions constituted of bricks 23, 24 (Fig. 2) and 37, 38, 39 (Fig. 3) on one side, and bricks 17, 18 (Fig. 2) and 31, 32 (Fig. 3) on the other side, the monolithic portions of one wall being disposed in surface contact with those of a contiguous wall defining the regenerator compartments to provide the partition walls having expansion joints 21, 21' therein which reinforce or buttress the cross-wise extending wall 13. The buttressing effect of the monolithic partition wall sections will be more evident from Fig. 6 wherein reference character A designates the partition wall sections constituted of bricks 17, 18, 31 and 32, and B designates the sections constituted of bricks 23, 24, 37, 38 and 39. It will be observed that the monolithic partition wall sections A and B constitute series of buttresses or ribs extending laterally from each side of each crosswise extending wall 13, thereby strengthening the walls 13; each partition wall section at its free end forms expansion joint 21 or 21' permitting the walls 13 to move toward and away from each other upon contraction and expansion of the oven.

In the structure shown on the drawings, before leakage of gas from one regenerator compartment to another can take place through the expansion joints, it is necessary for the gas to travel through the tortuous and extended path corresponding to the contacting surfaces between bricks 19, 20; 18, 23; 18, 24 and 24, 25, as well as through the two expansion joints 21 and 21', in the case of the even numbered courses, the path through the odd numbered courses being of substantially the same extent and configuration, as is evident from Fig. 3. To further minimize leakage of gas, one or more openings 60 may be formed between the contacting surfaces of bricks 18 and 24 and 32 and 37 or at any desired point in the contacting plane 61 between the monolithic portions constituting each partition wall 14. These openings are packed with dry comminuted silica, providing a barrier for flow of gas therethrough. In practice it has been found that with the construction and design shown on the drawings, substantially no leakage of gas from one regenerator compartment into a contiguous compartment takes place.

It will be noted that this invention provides a brick-work partition wall construction for a coke oven battery which permits longitudinal expansion of the battery while at the same time minimizing, if not completely preventing, leakage of gas from one regenerator compartment to another, and which partition walls reinforce or buttress the cross-wise extending regenerator walls.

It will be understood that this invention is not limited to the exact details of construction shown or described, for obvious modifications will occur to a person skilled in the art.

What is claimed is:

1. A coke oven battery having coking chambers, cross-wise extending walls defining regenerators below and in parallel relation to said coking chambers, and longitudinally extending partition walls dividing said regenerators width-wise of the battery into a plurality of compartments, each of said partition walls in each regenerator comprising two portions joined respectively at one end to contiguous cross-wise extending walls defining said regenerator, the other end of each portion being spaced from the other cross-wise extending wall of said regenerator to provide an expansion joint space, the said portions being in slidable contact with each other, each of said portions of said partition wall constituting a buttress extending from and strengthening one of said crosswise extending walls.

2. In a coke oven battery, cross-wise extending regenerator walls, each having at spaced points therealong extending from opposite sides thereof and bonded thereto, one end of partition wall sections, the other end of said partition wall sections being disposed to provide expansion joint spaces in the partition walls separating contiguous regenerator compartments, the partition wall sections of two contiguous cross-wise extending walls being disposed in pairs with the individual sections of each pair in contact with each other, whereby the said pairs of partition wall sections define partition walls having expansion joint

spaces therein, which walls buttress the cross-wise extending regenerator walls.

3. In a coke oven battery in combination, a wall, a second wall extending in spaced relation to said first named wall, a third wall extending between said two spaced walls, said third wall comprising two wall sections, one of said sections extending from said first wall to said second wall and defining with said second wall an expansion joint space, the other of said wall sections extending from said second wall to said first wall and defining with said first wall an expansion joint space, said wall sections forming buttresses extending from and strengthening said first and second walls.

4. A regenerator for a coke oven battery comprising a first wall extending crosswise of said battery, a second wall extending crosswise of said battery in substantially parallel relation to said first wall, a partition wall bonding with said first and second walls, said partition wall comprising two substantially monolithic portions each extending with a surface thereof in a vertical plane, a vertical surface of one portion slidably contacting a vertical surface of the other portion, one end of one of said portions bonding with said first crosswise extending wall and the other end of said portion defining an expansion joint space adjacent the second crosswise extending wall, one end of the other of said portions bonding with said second crosswise extending wall and the other end of said other portion defining an expansion joint space adjacent said first crosswise extending wall, said expansion spaces permitting longitudinal expansion of the battery, said monolithic portions constituting buttresses extending in the longitudinal direction of the battery from said crosswise extending walls and strengthening the same and means disposed on the contacting surfaces of said monolithic portions to prevent leakage of gas through said partition wall.

CHARLES V. McINTIRE.
